CLAIM

The ornamental design for an ear pendant, as shown and described.

DESCRIPTION

FIG. 1 is a front view of the ear pendant;

FIG. 2 is a rear view thereof;

FIG. 3 is a right side view thereof, the left side view being a mirror image thereof;

FIG. 4 is a top view thereof;

FIG. 5 is a bottom view thereof;

FIG. 6 is a front top perspective view thereof; and,

FIG. 7 is a rear top perspective view thereof.

The broken lines shown in the drawings represent unclaimed portions of the ear pendant and form no part of the claimed design.
